His Attorney.

UNITED STATES PATENT OFFICE.

JOHN R. HEWETT, OF SCHENECTADY, NEW YORK, ASSIGNOR TO GENERAL ELECTRIC COMPANY, A CORPORATION OF NEW YORK.

SIGNALING APPARATUS.

Application filed August 27, 1918. Serial No. 251,698.

My present invention relates to signaling devices, and more particularly to submarine signaling devices which are automatically operated by the receipt of sound waves to transmit any desired form of signal.

One of the objects of my invention is to provide a signaling device which may be located at any desired point and which may be actuated by sound waves in such a way as to automatically transmit a signal of a predetermined character, the character of the signal transmitted being independent of the nature of the sound waves which actuate the device.

15 A further object of my invention is to provide a signaling system in which one or more of my improved signaling devices are employed and which will enable an observer supplied with suitable receiving apparatus to determine at some desired point the locality in which the sound, which actuates the signaling apparatus, originates.

Still another object of my invention is to provide a system which will enable an observer on a ship at sea to determine the approximate location of the ship by receiving the signals transmitted by one of my devices in response to sounds originating on the ship.

30 In carrying my invention into effect I provide a complete receiving and transmitting apparatus which is enclosed in a waterproof receptacle which may be submerged and rest on the bottom of the sea at any desired point. The receiving apparatus is so arranged that it will be actuated by sound waves produced in the water in the vicinity of the device. When the receiving apparatus is actuated by sound waves it automatically sets into operation the transmitting apparatus. The transmitting apparatus is arranged to transmit signals of any predetermined desired character. Different devices are arranged to transmit different characteristic signals. An observer who is equipped with suitable receiving apparatus within range of the transmitting apparatus of different devices and who knows the location of each signaling device and the characteristic signal of each device is able to tell from the signals which he receives the approximate locality in which the sounds originate which actuate the signaling devices to produce the signals.

35 When a boat comes within range of one of

my devices the sounds produced on the boat will actuate the device and cause it to transmit its characteristic signal. This will enable an observer on the boat who knows the location of the device actuated to determine 60 the approximate location of the boat.

The novel features which I believe to be characteristic of my invention are set forth with particularity in the appended claims. My invention itself, however, both as to its 65 organization and method of operation together with further objects and advantages thereof, will best be understood by reference to the following description taken in connection with the accompanying drawing in 70 which I have illustrated partly in section and partly by diagram a device which is organized in accordance with my invention.

As indicated in the drawing a watertight casing 1 is provided in which the complete 75 apparatus is enclosed. This casing may be made in the form of the frustum of a cone or pyramid so that when it rests on the bottom of the sea any cable or other device which is dragged along the bottom will 80 readily pass over the casing. In the top of the casing 1 a sound responsive and sound producing apparatus is mounted. This may be of the form commonly known as a Fessenden oscillator. As indicated in the drawing, this comprises a diaphragm 2 which is secured to a movable member 3 consisting of a metal cylinder which is free to move between pole pieces 4, 5, 6 and 7, and a stationary central core 8. A constant magnetizing field for the operation of the device may be produced by supplying current to the winding 9. In order to produce a movement of the cylinder 3 and diaphragm 2 an alternating current may be supplied to the 90 winding 10 which is wound on the central core 8. The movement of the diaphragm 2 in this way will produce sound waves in the water, the nature of the sound waves thus produced being dependent upon the nature 100 of the current supplied to the winding 10.

The device which I have described is also a sound responsive device; that is, sound waves in the water will produce a movement of the diaphragm 2. In the usual operation of the device this movement of the diaphragm is caused to generate an alternating current in the winding 10 and this current may be caused to flow through a telephone receiver to reproduce the sounds which 110

actuate the diaphragm 2. In order to generate an alternating current in this way, however, it is necessary that direct current be supplied to the winding 9. This would 5 mean that in the present case, in which it is desired that the apparatus should be adjusted to respond to sound waves all of the time, it would be necessary to supply direct current to the winding 9 all of the time. 10 I have overcome this disadvantage, and arranged the device in such a way that it will act in response to sound waves at any time and be automatically actuated to transmit a desired signal, in the following manner: 15 On the lower end of the shaft 11 which moves with the diaphragm 2, I provide a curved reed 12 which is preferably resonant to the same frequency as the diaphragm 2. When the diaphragm 2 moves in response 20 to sound waves an intensified movement is produced of the free end of the reed 12. This free end of the reed 12 carries a microphone 13 which is connected to the input circuit of an amplifier 14 which may be of 25 the type described in De Forest Patent 879,532. When the microphone is not in operation a circuit from battery 15 is completed through the output circuit of the amplifier and the coil 16. Within the coil 16 30 is located a movable member 17 which carries a permanent magnet 18 and a contact member 19. When current passes through the coil 16 the member 17 is held in the position indicated, the axis of the magnet 18 35 being parallel to the axis of the coil. When the diaphragm 2 is actuated the consequent vibration of the reed 12 causes the current through the microphone 13 to vary and the amplifier 14 is so arranged that this variation 40 in the microphone current will produce a large decrease in the current in the output circuit of the amplifier. As a result the current through coil 16 will no longer be strong enough to hold the member 17 in the position 45 indicated and the member 17 will be caused to revolve around its axis 20 by the action of the coiled spring 21 until the member 19 bridges contacts 22.

The bridging of contacts 22 closes the circuit of the solenoid 23 which is supplied with current by battery 23^a. When the solenoid 23 is thus energized the core 24 is pulled down in opposition to the spring 25 and carries with it the flexible cord 26, 50 thereby producing a rotation of the wheel 27. The wheel 27 carries a member 28 which bridges the contacts 29 when the solenoid core has reached the lower limit of its travel. When contacts 29 are bridged the circuit 55 from the battery 23^a through the solenoid 30 is completed. This solenoid operates a series of switches 31, 32, 33, 34, 35, 36. The energization of the solenoid 30 opens switch 31 and closes all of the other switches of the 60 series. The closing of switch 32 connects the battery 23^a to windings 9 and thus energizes the field of the oscillator. The closing of switch 33 connects the motor 37 to the battery 23^a and thus starts the motor in operation. The closing of switch 35 causes 70 current to be supplied from the battery 23^a to the slip rings 38 which are mounted on the shaft of motor 37. Switch 34 closes a circuit through the commutator 39 and the winding 10. This commutator is connected 75 to the slip rings 38 in such a way that when the motor 37 is operated an alternating current may be supplied to the winding 10. The opening of switch 31 opens the circuit through solenoid 23. As a result this solenoid is deenergized, the plunger 24 moves upward with the assistance of spring 25 and the wheel 27 starts to return to its normal position under the influence of the spring 80 40. It should here be noted that the closing 85 of switch 34 does not immediately close the circuit through winding 10, but that this circuit includes a pair of contacts 41 in the form of brushes which bear against the periphery of wheel 27. Wheel 27 is preferably 90 made of insulating material and its periphery is provided with metal blocks 42 which bridge contacts 41 when the wheel is returning to its normal position. While contacts 41 are thus bridged by the metal 95 blocks 42 the circuit of winding 10 will be closed and diaphragm 2 will be actuated to produce a sound wave. This sound wave will continue as long as contacts 41 are bridged by one of the metal blocks 42. 100 These metal blocks 42 are so arranged on the periphery of the wheel 27 that sounds will be successively produced by the diaphragm 2 according to some predetermined scheme. By varying the arrangement of 105 these metal blocks any desired succession of sounds can be produced; each individual group of sound waves may be made of short or long duration and the intervals between successive groups may also be varied. In 110 this way any device constructed may be caused to transmit a characteristic signal which may be made to be different in some respect from the signal which would be transmitted by any other device. The tone of the 115 sound produced will, of course, be dependent upon the frequency of the alternating current supplied to the winding 10. By using different frequencies different tones may be produced and hence the signals transmitted from 120 different devices may also be differentiated by tone as well as by the length and order of succession of the groups of sound waves produced. The sounds produced will also 125 be of much greater intensity than the sounds which actuate the device so that the signals transmitted may be heard at a much greater distance than the original sounds which actuate the device.

In order to provide for a uniform move- 130

ment of the rotating member 27 it may be desirable to employ a damping device of some form upon this member. In the present case I have illustrated for this purpose a vane 43 which is attached to the small gear wheel 44, this small gear wheel being driven by the larger wheel 45 which is mounted on the same shaft as the member 27.

As soon as the wheel 27 starts to return to its normal position the circuit of solenoid 30 is broken. If the switches controlled by this solenoid were at once opened no signals would be transmitted. On this account these switches should be provided with some form of time limit device, such, for example, as a dash-pot 46, to hold them closed until the desired signals have been transmitted.

In order to prevent the transmission of signals from affecting the control apparatus the switch 36 is provided to close a circuit through the solenoid 47. This solenoid controls a switch 48 which closes the circuit through the coil 16 and holds it closed until after the signals have been transmitted. This switch also may be provided with a time limit device, such, for example, as the dashpot 49, which will hold it closed for a predetermined time after switch 36 is opened. This will provide for a convenient time interval between the transmission of successive sets of signals in case the sounds which actuate the sound responsive device continue.

It will be apparent from the above description that an appreciable time must elapse from the instant when the diaphragm 2 is first actuated by sound waves before the member 28 will bridge the contacts 29 to actuate the transmitting apparatus. On this account the transmitting apparatus will not be affected by sounds of short duration such as those which might be caused by an explosion in the water, but will only be affected by sounds which continue for a predetermined period of time.

I have described one embodiment of my invention but I do not wish to be limited to the precise form shown as it will be apparent to one skilled in the art that many changes in the structural details and circuit connection as well as in the type of apparatus used may be made without departing from the scope of my invention as set forth in the appended claims. For example, I have shown a device which is capable of both responding to sounds and producing sounds. While the use of such a device may be convenient it is by no means essential as separate devices may readily be employed to accomplish the two different functions.

What I claim as new and desire to secure by Letters Patent of the United States, is:—

1. A signaling apparatus comprising sound responsive means and means adapted

to be controlled by said sound responsive means and adapted to produce and transmit through water for predetermined time intervals sounds of a predetermined desired character different from that of the sounds which actuate the sound responsive means.

2. A signaling apparatus comprising sound responsive means and means adapted to be controlled by said sound responsive means for producing and transmitting through water sounds of a predetermined desired character for definite time intervals whenever said sound responsive means is actuated for a predetermined period of time.

3. A signaling apparatus comprising sound responsive means which is responsive to sounds of different characters and means adapted to be controlled by said sound responsive means and adapted to produce an intensified actuation of the sound responsive means and transmit through water only sounds of a single desired character which is independent of the character of the controlling sound.

4. A signaling apparatus comprising a sound responsive and sound producing device and means adapted to be controlled by said device when it is actuated by sounds to cause it to produce for definite time intervals which are independent of the duration of the actuating sounds, sounds of a different character than those by which it is actuated.

5. A signaling apparatus comprising a sound responsive and sound producing device and means adapted to be controlled by said device when it is actuated by sounds for a predetermined period of time to cause it to produce for definite time intervals which are independent of the duration of the actuating sounds, sounds of a different character than those by which it is actuated.

6. A submarine signaling apparatus adapted to be submerged in the water, comprising sound responsive means and means adapted to be controlled by said sound responsive means for producing in the water for definite time intervals sounds of a predetermined desired character which is different from the character of the sounds actuating said sound responsive means.

7. A signaling apparatus comprising a diaphragm adapted to be directly actuated by sound waves and means adapted to be controlled by the actuation of said diaphragm and so adjusted as to produce a further actuation of said diaphragm to produce thereby sound waves of a predetermined desired character.

8. A signaling apparatus comprising a diaphragm adapted to be directly actuated by sound waves and means adapted to be controlled by the actuation of said diaphragm and so adjusted as to produce a further actuation of said diaphragm to produce sig-

naling waves of a predetermined desired character.

9. A signaling apparatus comprising a diaphragm adapted to be directly actuated by sound waves and means adapted to be controlled by the actuation of said diaphragm and so adjusted as to produce an intensified actuation of said diaphragm and thereby produce signaling waves of a predetermined desired character.

10. The method of operating a sound responsive and sound producing device which consists in directly actuating said device by sound waves and causing the actuation of said device to produce for definite time intervals which are independent of the duration of the actuating sounds an intensified actuation of the device and thereby produce sounds of a predetermined desired character.

11. The method of operating a signaling system which comprises sound responsive and signal producing apparatus which consists in directly actuating the sound responsive apparatus by means of sound waves and causing the actuation of the sound responsive apparatus to produce an actuation of the signal producing apparatus to transmit during successive definite time intervals signals of a predetermined desired character different from that of the sound waves actuating the sound responsive apparatus.

12. The method of operating a signaling system which comprises a sound responsive and a sound producing diaphragm which consists in directly actuating said diaphragm by means of sound waves and utilizing the actuation of said diaphragm to produce an intensified actuation of said diaphragm of a character differing from the original actuation.

13. The method of operating a sound responsive and sound producing device which consists in directly actuating said device by sound waves and utilizing any actuation of said device which continues for a predetermined time interval to produce an intensified actuation of the device and thereby produce during successive definite time intervals sounds of a predetermined desired character different from that of the sound waves by which it is actuated.

14. A signaling apparatus comprising a sound responsive device and means adapted to be automatically set into operation by the actuation of said sound responsive device for producing and transmitting through water signals of a predetermined desired character for definite time intervals with definite time intervals between signals.

15. A signaling apparatus comprising a sound responsive device and means adapted to be automatically set into operation by the actuation of said sound responsive device for a predetermined period of time for pro-

ducing and transmitting through water signals of a predetermined desired character for definite time intervals with definite time intervals between signals.

16. A signaling apparatus comprising a diaphragm adapted to be actuated by sound waves and means adapted to be controlled by the actuation of said diaphragm for a predetermined period of time for producing an intensified actuation of said diaphragm and thereby producing sounds of a single predetermined desired character which is different from the character of the sounds which actuate the diaphragm.

17. A signaling apparatus comprising a diaphragm adapted to be actuated by sound waves and means adapted to be automatically set into operation by the actuation of said diaphragm for a predetermined period of time to produce an intensified actuation of said diaphragm and thereby produce sounds of a predetermined desired character.

18. A signaling apparatus comprising sound responsive means which is adapted to be actuated by sounds of small intensity transmitted through the water and means adapted to be automatically set into operation by the actuation of said sound responsive means to produce and transmit through water sounds of a predetermined desired character and of greater intensity and different character than those actuating the sound responsive means.

19. A signaling apparatus comprising sound responsive means which is adapted to be actuated by sounds of different characters of small intensity transmitted through the water which continue for a predetermined period of time and means adapted to be automatically set into operation by the actuation of said sound responsive means to produce and transmit through water sounds of a predetermined single desired character only and of greater intensity than those actuating the sound responsive means.

20. A signaling apparatus comprising sound responsive means which is adapted to be actuated by sounds of different characters which continue for a predetermined period of time, and means adapted to be automatically set into operation by the actuation of said sound responsive means to produce and transmit through water groups of sound waves of a definite tone for definite time intervals and with definite time intervals between successive groups.

21. A signaling apparatus comprising sound responsive means adapted to be actuated by sounds transmitted through water and means adapted to be controlled by said sound responsive means and adapted to produce and transmit through water sounds of a predetermined desired character for definite time intervals which are independent of the duration of the actuating sounds.

22. A signaling apparatus comprising sound responsive means adapted to be actuated by sounds of different characters transmitted through water, and means adapted to be controlled by said sound responsive means and adapted to produce and transmit through water sounds of a single desired character for definite time intervals which are independent of the duration of the actuating sounds.

23. A signaling apparatus comprising sound responsive means adapted to be actuated by sounds transmitted through water and means adapted to be controlled by said sound responsive means and adapted to produce and transmit through water for definite

time intervals sounds of a predetermined desired character whenever said sound responsive means is actuated for a predetermined period of time.

24. A signaling apparatus adapted to be submerged in water comprising a sound responsive and sound producing device, and means adapted to be controlled by said device when it is actuated by sounds transmitted through water to cause it to produce and transmit through water for definite time intervals sounds of a different character than those by which it is actuated.

In witness whereof, I have hereunto set my hand this 26th day of August, 1918.

JOHN R. HEWETT.
